UNITED STATES PATENT OFFICE.

LOUIS TOTH, COLOMAN KONYVES, AND FRANK STRIEFFLER, OF PHILADELPHIA,
PENNSYLVANIA.

JACQUARD MECHANISM FOR CIRCULAR-KNITTING MACHINES.

Application filed May 5, 1922. Serial No. 558,583.

To all whom it may concern:

Be it known that we, LOUIS TOTH, COLOMAN KONYVES, and FRANK STRIEFFLER, a citizen of the United States, and citizens of

5 Hungary, respectively, residing at Philadelphia, in the county of Philadelphia, and State of Pennsylvania, have invented new and useful Improvements in Jacquard Mechanism for Circular-Knitting Machines, 10 of which the following is a specification.

One object of our said invention is the provision of a simple, reliable and efficient jacquard feeding mechanism for circular knitting machines.

15 Another object of the invention is the provision of an improved drum construction.

Another object is the provision of an improved cylinder construction.

20 To the attainment of the foregoing, the invention consists in the improvement as hereinafter described and definitely claimed.

In the accompanying drawings, forming part of this specification:—

25 Figure 1 is a view in vertical section showing our improvement together with so much of a circular knitting machine as is necessary to show the application of the improvement.

30 Figure 2 is a detail view showing the ratchet mechanism of the hexagonal roller.

Figure 3 is a perspective of one of the drum plates.

35 Figure 4 is a similar view of one of the filler members of the drum.

Figure 5 is a view showing the improved feeding mechanism.

40 Figures 6 and 7 are perspective views of the plates comprised in the cylinder of the machine.

Figure 8 is a view showing the feeding mechanism in side elevation.

Figure 9 is a perspective showing the bar and spring rods carried thereby.

45 Similar numerals designate corresponding parts in all of the views of the drawings.

The machine base is designated by 3, and in the same is seated a table 2 designed to be rotated by the ordinary or any other appropriate means not of our invention, and, therefore, not shown.

50 Fixed with respect to and movable with the table 2 are cams 14 and 16 relatively arranged as shown in Figures 1 and 5.

55 Fulcrumed at an intermediate point in its

length in a standard 38 on the base 3 is a vertically-swinging lever 17, Figures 1 and 5, with a roller 13 at its inner end and above the rotary table 2.

Pendent spaced hanger-brackets 27 are 60 carried by the base 3 which is of annular formation, and supported in the said brackets 27 is a rock shaft 37 on which is fixed vertically swinging arms 24, 24^x. A link 23 is interposed between and connects the outer end of the lever 17 and the outer end of the arm 24. At their inner ends the arms 24^x of the rock shaft 37 are connected to vertically-slidable bars 28, guided in the brackets 27. The said slidable bars carry a hexagonal roller 29, preferably of wood, and provided with sockets 29^x, Figures 1 and 8, the roller 29 being arranged between the bars 28 and the trunnions at the ends of the rollers being journaled in the said bars 28. 70 One of the said trunnions has fixed thereto a ratchet wheel 36 for cooperation with a pawl 35 mounted and relatively arranged as shown in Figure 2 on one of the brackets 27. Manifestly when deemed expedient it is 75 within the purview of our invention to duplicate the said ratchet mechanism at the opposite end of the roller 29.

It will be apparent from the foregoing that incident to each complete revolution of 80 the table 2, the cam 14 by cooperation with the anti-friction roller 13 rocks the lever 17 and depresses the link 23 and arm 24 with the result that the arms 24^x and the slidable bars 28 and roller 29 are raised. 85 As the cam 14 passes out of engagement with the roller 13, the slidable bars 28 and the roller 29 gravitationally return to their normal, lower positions. As the roller 29 moves downward the ratchet mechanism described turns the roller 29 through one sixth of a revolution so as to place a fresh set of sockets 29^x uppermost. 90

Appropriately guided in a housing 17^x fixed on the base 3 is an endwise movable 100 radially-disposed plunger 18. At the inner end of said plunger 18 is an anti-friction roller or wheel 15 arranged to cooperate with the cam 16, the said cam 16 being so arranged, relatively to the cam 14, that the plunger 18 will be moved inwardly immediately prior to the rocking of the lever 17 by the cooperation of the cam 14 with the roller or wheel 13. The plunger 18 is 105 moved inwardly against the action of a 110

- spring 19 in the housing 17* and interposed between the inner end of said housing and an abutment 18* on plunger 18. Movable by the plunger 18 is a vertically swinging arm 21, fixed with respect to a rocking bar 25, Figures 1, 5, 8 and 9. The said rocking bar 25 is mounted to rock in brackets 22 on the base 3, and is equipped with a plurality of inwardly extending, spaced resilient rods 26. The said resilient or spring rods 26 are engaged with vertically movable pins 31, the said pins 31 being pivotally connected to the outer arms of vertically swinging, levers 33. The said levers 33 are fulcrumed at 34 and are arranged as shown in Figure 1 relative to needles 34* so as to raise the said needles when the pins 31 are thrust downwardly. It will be apparent from the foregoing that inward movement 20 of the plunger 18 by the cam 16 will be attended by downward movement of the pins 31 and by rocking of the levers 33 to lift the needles 34*. On outward movement of the plunger 18 under the action of the spring 19, the pins 31 will be raised, and the levers 33 will be rocked to permit of gravitation of the needles 34*. Downward movement of the pins 31 is controlled by an apertured pattern 20*, mounted on the roller 29, the said pattern 20* being provided with sets of apertures 21*, differently arranged so that on rocking of the bar 25 some of the pins 31 will be permitted to move downwardly as described while others 35 of the pins 31 will be prevented by the pattern from moving downwardly into the sockets 29* of the roller 29. Manifestly the resilient or springy character of the rods 26 will render this feasible.
- 40 The levers 33 are pivoted in the drum which includes plates 8, Figures 1 and 3, filler members 9, an inside ring 10, and an outside ring 32. The inside ring 10 is beveled to hold the plates 8 and members 9 in position, and the outside ring 32 is crowded on the plates to solidly retain the same in assembled relation. The cylinder is made up of plates 6 and 7, Figures 1, 6 and 7, held together through the medium of rings 11 and 12, the ring 11 being fastened by screws 11* or other appropriate means to the drum ring 10.
- 45 As will be noted by reference to Figure 1, the upward movement of the needles 34* by the action of the levers 33 is limited by lateral enlargements 5 on the needles bringing up against an inwardly directed flange on an annulus superimposed upon and fixed to the table 2.
- 50 In the operation of the improvement it will be understood that when the cam 14 rocks the lever 17 and thereby raises the roller 29 to the highest point, the cam 16 moves the plunger 18 inwardly and thereby depresses the resilient rods 26. Where a
- hole is in the pattern or pattern paper 20* the pin 31 above said hole will be moved downwardly by its spring rod to rock the lever 33 connected to the pin. The needle connected to said lever will be raised. The raised needles have a yarn carrier (not shown), with different color yarn between the other two standard yarn carriers, and the first-named carrier feeds the yarn in the needles which are raised as stated under the control of the pattern or pattern paper when the stitch cam reaches the needles that make the stitch and brings the other color yarn out on the front and marks the design.
- 55 Having described our invention, what we claim and desire to secure by Letters-Patent, is:—
1. The combination in a circular knitting machine, of a base, a rotary table, a circular series of vertically-movable needles carried by the table, a group of needle-raising levers carried by the base, pins connected to and pendent from the outer arms of the levers, a hexagonal roller with sockets in its sides disposed under the pins, a pattern with sets of apertures on the roller, gravitational means carrying said roller, means to turn the roller through a part of a revolution on downward movement of the gravitational means, means controlled by the rotary table to raise and release said gravitational means, and means controlled by the rotary table to depress the pins, the latter means including resilient connections, one to each pin. 60
2. The combination in a circular knitting machine, of a base, a rotary table, a circular series of vertically-movable needles carried by the table, a group of needle-raising levers carried by the base, pins connected to and pendent from the outer arms of the levers, a hexagonal roller with sockets in its sides disposed under the pins, a pattern with sets of apertures on the roller, gravitational means carrying said roller, means to turn the roller through a part of a revolution on downward movement of the gravitational means, a cam on the rotary table, a lever fulcrumed on the base to swing vertically and operable by said cam and connected with said gravitational means to raise the latter, a second cam on the rotary table, a plunger carried by the base and movable endwise in one direction by said second cam, a spring to move the plunger in the opposite direction, and resilient connections, one to each pin, operable by said plunger to depress the pins. 65
3. The combination in a circular knitting machine, of a base, a rotary table, a circular series of vertically-movable needles carried by the table, a group of needle-raising levers carried by the base, pins connected to and pendent from the outer arms of the levers, a hexagonal roller with sockets in its sides 70
- 120
- 125
- 130

disposed under the pins, a pattern with sets of apertures on the roller, gravitational means carrying said roller, means to turn the roller through a part of a revolution on downward movement of the gravitational means, a cam on the rotary table, a lever fulcrumed on the base to swing vertically and operable by said cam and connected with said gravitational means to raise the latter, a second cam on the rotary table, a plunger carried by the base and movable endwise in one direction by said second cam, a spring to move the plunger in the opposite direction, and a rocking bar having an upstanding arm movable by said plunger and also having a series of resilient rods connected with the pins, one rod to each pin.

4. The combination in a circular knitting machine, of a base, a rotary table, a circular

series of vertically-movable needles carried by the table, a group of needle raising levers carried by the base, pins connected to and pendent from the outer arms of the levers, pattern means, gravitational means carrying said pattern means, means to shift the pattern means on downward movement of the gravitational means, means controlled by the rotary table to raise and release said gravitational means, and means controlled by the rotary table to depress the pins, the latter means including resilient connections one to each pin.

In testimony whereof we affix our signatures.

LOUIS TOTH.
COLOMAN KONYVES.
FRANK STRIEFFLER.
